CLAIM

The ornamental design for an absorbent article as shown and described.

DESCRIPTION

The patent or application file contains at least one drawing executed in color. Copies of this patent or patent application publication with color drawing(s) will be provided by the Office upon request and payment of the necessary fee.

FIG. 1 is a perspective view of an absorbent article showing the front, bottom, and right sides of the absorbent article;

FIG. 2 is a view of the front side of the absorbent article of FIG. 1;

FIG. 3 is a view of the right side of the absorbent article of FIG. 1;

FIG. 4 is a view of the back side of the absorbent article of FIG. 1;

FIG. 5 is a view of the left side of the absorbent article of FIG. 1;

FIG. 6 is a view of the top side of the absorbent article of FIG. 1; and,

FIG. 7 is a view of the bottom side of the absorbent article of FIG. 1.

The broken lines shown are for illustrative purposes only and form no part of the claimed design.

Any patent application or patent to which this application claims priority or benefit thereof, is hereby incorporated herein by reference in its entirety. All of the material from the patent or patent applications which is essential to the claimed design is included herein. Any material in the patent or patent applications which is not present herein forms no part of the claimed design.
